TWO COMPARTMENT BOX

Roy C. Potts, Takoma Park, Md.

Application April 26, 1944, Serial No. 532,814

6 Claims. (CL 229—15)

It is an object of this invention to provide a two-compartment shipping case which can be made of large size without, however, requiring the production of blanks having unwieldy dimensions.

It is a further object of this invention to provide a box of the class described which may be opened, collapsed and re-used with minimum injury to the box.

It is a further object of this invention to provide a two-compartment shipping case formed from two identical blanks in which each compartment has complete top and bottom closure flaps.

It is a further object of this invention to provide a box of the class described in which only two types of blanks are involved and in which die cutting in the formation of the blanks is reduced to a minimum.

It is a further object of this invention to provide a two-compartment box in which the two compartments are formed and secured to each other by means of a single line of stitching on each side of the assembled box.

It is a further object of this invention to provide a two-compartment box having all of its vertical walls of double thickness and having closure flaps corresponding to the structure of a regular slotted carton.

The above and other objects will be made clear in the following detailed description, taken in connection with the annexed drawings, in which:

Figure 1 is a plan view of the body forming type of blank;

Fig. 2 is a plan view of the closure-forming type of blank;

Fig. 3 is a plan view of a box assembled from the blanks of Figs. 1 and 2;

Fig. 4 is a section taken on the line 4—4 of Fig. 3;

Fig. 5 is a sectional view similar to Fig. 4, but showing the closure panels in closed position;

Fig. 6 is a plan view of a blank showing the application of my invention to the ordinary slotted type container;

Fig. 7 is a plan view of a two-compartment box formed by joining two blanks of the type shown in Fig. 6;

Fig. 8 is a perspective view showing the box of Fig. 7 with all of the flaps in closed position;

Fig. 9 is a plan view of a blank forming a two-compartment box body;

Fig. 10 is a plan view of a blank to be combined with the blank of Fig. 9 to provide double thickness walls and top and bottom closure flaps; and

Fig. 11 is a plan view of the carton formed when the blanks of Figs. 9 and 10 are combined and erected.

In Fig. 1 I show one of the two types of blanks

from which my improved box is formed. Two identical blanks of the form of Fig. 1 are joined to form the two compartment box body. The blank is indicated generally as 10 and is made up of a closure flap 12, wall panels 14, 16 and 18 and a combination wall panel and closure flap 20. A score line 13 divides flap 12 from panel 14; a score line 15 divides panel 14 from panel 16; a score line 17 divides panel 16 from panel 18; and a score line 19 divides panel 18 from the combination flap and panel 20.

Panel 14 has an auxiliary flap 30 at its upper edge defined by a score line 31 and an auxiliary flap 32 at its lower edge defined by a score line 33. Panels 16 and 18 have identical flaps 34, 36, 38 and 40 defined by prolongations of the score lines 31 and 33. The combination flap and panel 20 has similar auxiliary flaps 42 and 44 similarly defined. It is to be noted, however, that flaps 42 and 44 terminate short of the end of the combination flap and panel 20 by an amount equal to the width of the closure flap 12. The extremities of each of the several auxiliary flaps are cut away along 45° lines for a purpose presently to be described.

In Fig. 2 I show the other of the two types of blanks from which my improved box is formed. This blank is indicated generally by the reference numeral 50 and comprises an end wall panel 52 having a top closure panel 54 at one side, defined by a score line 56, and a bottom closure panel 58 at the opposite side defined by a score line 60. At the opposite side of the bottom closure panel 58 is a securing flap 62 defined by a score line 64. At the opposite side of the top closure panel 54 is a closure securing flap 66 defined by a score line 68.

A two compartment box body is formed by folding and securing together two identical blanks 10. This is accomplished, as shown in Fig. 3, by bringing the free edge of the combination panel and flap member 20 into contact with the flap member 12. The blank is folded through 90° along score lines 15, 17 and 19 and the flap 12 is folded 90° from the panel 14 but in the opposite direction from the folding of score lines 15, 17 and 19.

Each blank 10, therefore, forms a four walled compartment with the panels 14 of the two blanks set adjacent each other. These panels 14 are spaced apart a distance sufficient to accommodate twice the thickness of the board in blank 50. It is to be noted that the superimposed portions of flap 12 and panel 20 of each compartment lie on opposite sides of the assembled box and each overlies one side of a panel 16. The assembly is completed by running a row of staples 75 down each side of the box, penetrating the panel 20, the flap 12 and the panel 16 at each side. With the box in this condition the auxiliary flaps 30,

34, 38, 42, etc., may be folded at 90° to their respective panels and thereby form a base to support the closure panels of the blank 50.

Two blanks 50 are applied to opposite sides of the two compartment body. In each case the central panel 52 is secured to a panel 18 of each of the blanks 10, preferably by a line of staples penetrating both panels and running down the outer margins. The box is closed, as indicated in Fig. 5, by bringing closure panels 54 over the top of each compartment, and closure panels 58 over the bottom of each compartment. Top closure securing flaps 66 and bottom closure securing flaps 62 are thrust between the separated panels 14 at the center of the two compartment box body.

In Fig. 5 a special feature is illustrated which will be useful where the contents of the box is relatively heavy. In this case perforations are formed in the panels 14 of blanks 10 and in the bottom closure securing flaps 62 of the blanks 50. These perforations are so formed that when the parts are in the condition illustrated in Fig. 5, they fall into registry. Any suitable securing means may be passed therethrough. If, however, the box is to be collapsible and re-usable, the securing means should be removable. One suitable form of securing means is shown in my Patent No. 2,352,407, dated June 27, 1944, and another suitable form is shown in my application Serial No. 532,815, filed of even date herewith.

It is to be noted that the improved two compartment box has its body, including the dual partition walls, completed by only two rows of staples, and that only four more rows are needed to secure the closure panels. This has not heretofore been accomplished, so far as I am aware. The tuck-in flaps on the blanks 50 make a secure closure which may be reopened and reclosed as often as necessary without damage to the material of the box. When the flaps 62 and 66 of the blanks 50 have substantial depth, and this will usually be the case, they are almost perfectly reliable against accidental displacement.

When it is desired to collapse the box, panels 54 and 58 of blank 50 are folded back substantially against the panel 18 of blank 10; the auxiliary flaps of blank 10 are folded back to lie in the planes of their respective panels, and the box body then collapses into flattened condition along the several score lines of the blank 10.

The fact that only two types of blanks are involved makes for real economy of manufacture, and for efficiency in the assembly operation as well. The blanks themselves are extremely simple in design, and die cutting has been minimized. This becomes quite important when solid fiber boards of substantial caliper are involved.

Referring now to Fig. 6, I show a blank 100 comprising an end flap 102 defined by a score line 104, a wall panel 106 defined by a score line 108, a wall panel 110 defined by a score line 112, a wall panel 114 defined by a score line 116, and a fourth wall panel 118. Wall panel 106 has a top closure flap 103 defined by a score line 103' and a bottom closure flap 105 defined by a score line 105'. Wall panel 110 has a top closure flap 107 defined by a score line 107' and a bottom closure flap 109 defined by a score line 109'. Wall panel 114 has a top closure flap 111 defined by a score line 111' and a bottom closure flap 113 defined by a score line 113'. Wall panel 118 has a top closure flap 117 defined by a score line 117' and a bottom closure flap 119 defined by a score line 119'. It is to be noted that the closure flaps 117 and 119 are

of less width than the panel 118 and the excess of width over that of the flaps substantially equals the width of flap 102.

As shown in Fig. 7, two blanks of the type shown in Fig. 6 may be joined to form a two-compartment box, each compartment of which has independent top and bottom closures of the familiar slotted carton type.

In each of the blanks, the flap 102 is bent outwardly at right angles to the panel 106. The blank is then given a rectangular conformation and the projecting portion of panel 118 is superimposed upon the flap 102. A second blank is similarly formed and the flaps 102 of each blank is superimposed upon the wall panels 110. A line of staples 120 (Fig. 8) is then applied through the projecting portion of the panels 118, the flaps 102 and the wall panels 110, to secure the two compartments together.

Any conventional means for closing cartons of the slotted type may be used, such, for example, as placing adhesive between the superimposed closure flaps or by running gummed tape, for example, across the flaps 107 and 117 in Fig. 8. I prefer, however, to utilize fasteners of the type disclosed in my copending application Serial No. 532,815, filed of even date herewith, and these may, if desired, be used in connection with pre-printed areas of self-sealing adhesive, as disclosed in said application.

One very important feature of this construction lies in the fact that a two-compartment box is formed using precisely the same number of staples which would be used for the ordinary corner securement of a one-compartment box, and with no more board consumed than is represented by the extra width of the panels 118. The two compartments are, however, very securely joined since the stitching passes through three thicknesses of board and, in any handling of the box, the stitching is stressed in shearing and not in tension, as would be the case were the compartments joined merely by stitching together the two abutting walls 106.

It is to be noted that the formation of the vertical walls of the two compartments in the form illustrated in Figs. 1 through 5 are identical to the form illustrated in Figs. 6, 7 and 8. The corner closure flap carrying walls, in either case, may be juxtaposed either in the abutting relationship of Figs. 6, 7 and 8, or in the spaced relationship of Figs. 1 through 5.

In Figs. 9, 10 and 11, I illustrate a box having its external walls of double thickness, but which, nevertheless, embodies the principles heretofore discussed. In Fig. 9, I show a blank 130 corresponding generally to the blanks of Figs. 1 and 6. The blank 130 comprises a corner closure flap 132, separated by a score line 132' from a partition panel 133. A score line 133' separates the partition panel 133 from a front (or rear) wall panel 134. A score line 134' separates the front wall panel 134 from an end wall panel 135, and a score line 135' separates the end wall panel 135 from a rear (or front) wall panel 136. The latter panel 136 exceeds in width the corresponding panel 134 by an amount equal to the width of the corner closure flap 132.

In Fig. 10, I show a blank 140 adapted to be combined with the blank 130 of Fig. 9. The blank 140 comprises a corner closing flap 141, a rear wall panel 142, an end wall panel 143, a front wall panel 144, and a second end wall panel 145, abutting the corner closure flap 141.

In Fig. 11, I show two blanks 130 combined

to form a two-compartment box body, with each corner closure flap 132 folded outwardly at right angles to the partition panel 133, and with the extra width of the panel 136 of one blank 130 overlying the corner closure flap 132 and a wall panel 134 of the other blank. The blank 140 of Fig. 10 is wrapped around the two compartment body. This doubles the thickness of all of the external walls. The corner closure flap 141 of the blank 140 underlies the rear wall panel 142 of that blank. Staples are passed through each side of the box and penetrate, on one side, the wall 142 of blank 140 and panels 136 and 134 and corner closure flap 132 of the blanks 130. On the other side, the same parts of blanks 130 are penetrated plus the wall 144 of blank 140.

A line of staples also passes through the wall 142 of the blank 140, the corner closure flap 141 of that blank and a wall 134 of one of the blanks 130. If desired, for additional strength, similar lines of staples may be placed at each corner of the box, through the walls 142 and 144 of the blank 140. Preferably, there should be no staples penetrating the end walls. Avoidance of such locations contributes to collapsibility, particularly when the blank 140 is triple scored at the sides of panels 143 and 145 as disclosed in my copending application Serial No. 532,817, filed of even date herewith. The flaps 142', 143', 144' and 145' of blank 140 form top and bottom closures for the final package. If desired, either or both of flaps 142' and 144' may be made of a width fully equal to the width of the box whereby to increase the strength of the closure by doubling the thickness of the top and bottom closures over the entire area covered. Such an expedient is illustrated in dotted outline in Fig. 11.

In connection with Fig. 11, it is to be noted that the distortion of the blank 140 in the walls 142 and 144 is greatly exaggerated. In practice, the thickness of board will vary between .045 and .080 inch, while the length of the walls will be from 18 inches to 36 inches. With the actual dimensions, therefore, the distortion will be negligible.

I claim:

1. A two-compartment box, each compartment having a top loading end opening upwardly and being formed from a single blank, the two blanks being mutually identical, each compartment having a corner closure comprising an extension of one wall superimposed upon a closure flap folded outwardly from the adjacent wall to form a projecting fin, said compartments having their respective corner-closure flap-carrying walls in juxtaposed relation and each having its projecting fin overlying a portion of one of the walls of the adjacent compartment, there being on each side of the assembled box a single line of stitching passing through a fin and a portion of the compartment wall under such fin.

2. A two-compartment box, each compartment having a top loading end opening upwardly and being formed from a single blank, the two blanks being mutually identical, each compartment having a corner closure comprising an extension of one wall superimposed upon a closure flap folded outwardly from the adjacent wall to form a projecting fin, said compartments having their respective corner-closure flap-carrying walls

in juxtaposed relation and each having its projecting fin overlying a portion of one of the walls of the adjacent compartment, there being on each side of the assembled box a single line of stitching passing through a fin and a portion of the compartment wall under such fin, each wall of each compartment having at least one closure flap of the slotted carton type.

3. A two-compartment box, each compartment having a top loading end opening upwardly and being formed from a single blank, the two blanks being mutually identical, each compartment having a corner closure comprising an extension of one wall superimposed upon a closure flap folded outwardly from the adjacent wall to form a projecting fin, said compartments having their respective corner closure flap-carrying walls in juxtaposed relation and each having its projecting fin overlying a portion of one of the walls of the adjacent compartment, there being on each side of the assembled box a single line of stitching passing through a fin and a portion of the compartment wall under such fin, each wall of each compartment having at each end thereof a closure flap of the slotted carton type.

4. A two-compartment box with a double wall between the compartments, each wall of said double wall being an extension of a side wall and bearing an end flap turned outwardly and overlapped by an extension of the abutting side wall of its compartment, said end flap and overlapped extension of the abutting side wall forming a fin projecting over an exterior side wall of the other compartment and being attached thereto by at least one row of staples.

5. A two-compartment, collapsible box formed from two pairs of blanks, the blanks of each pair being mutually identical, the blanks of one pair being joined to each other to form a two-compartment box body having a double wall between the compartments, each wall of said double wall being an extension of a side wall and bearing an end flap turned outwardly and overlapped by an extension of the abutting side wall of its compartment, said end flap and extension of the abutting side wall forming a fin projecting over an exterior side wall of the other compartment and being attached thereto by at least one row of staples, the blanks of the other pair being joined, each to one of the box body forming blanks in such manner as to form re-usable top and bottom closures for said box body.

6. A collapsible unitary box having a two-compartment, single-thickness box body formed from a pair of identical blanks, said box body having a double wall between the compartments, each wall of said double wall being an extension of a side wall and bearing an end flap turned outwardly and overlapped by an extension of the abutting side wall of its compartment, said end flap and extension of the abutting side wall forming a fin projecting over an exterior side wall of the other compartment and being attached thereto by at least one row of staples, the third blank surrounding all external walls of said box body to double the thickness thereof and being secured thereto by at least one row of staples in each side wall; there being a closure flap on each wall of said third blank, the closure flaps on opposed side walls overlying the closure flaps on opposed end walls when in closing position.

ROY C. POTTS.
